S. N. WIGHT.

ABSOLUTE PERMISSIVE BLOCK SIGNALING SYSTEM.
APPLICATION FILED APR. 28, 1916.

1,322,665.

Patented Nov. 25, 1919.

UNITED STATES PATENT OFFICE.

SEDGWICK N. WIGHT, OF ROCHESTER, NEW YORK, ASSIGNOR TO GENERAL RAILWAY SIGNAL COMPANY, OF GATES, NEW YORK, A CORPORATION OF NEW YORK.

ABSOLUTE PERMISSIVE BLOCK-SIGNALING SYSTEM.

1,322,665.

Specification of Letters Patent. Patented Nov. 25, 1919.

Application filed April 28, 1916. Serial No. 94,171.

To all whom it may concern:

Be it known that I, SEDGWICK N. WIGHT, a citizen of the United States, and a resident of the city of Rochester, in the county 5 of Monroe and State of New York, have invented a new and useful Improvement in Absolute Permissive Block-Signaling Systems, of which the following is a specification.

10 This invention relates to signaling systems for single track railroads, and more particularly to such signaling systems of the type commonly called absolute permissive block signaling systems, and disclosed in my Patent 15 No. 1,294,736, Feb. 18, 1919.

The primary object of this invention is to devise an absolute permissive block signaling system in which electrical energy derived from a single source may be used for 20 operating some or all of the signals and their associated controlling devices, and in which temporary interruptions of the current supplied from said single source will not affect the proper operation of the signaling system.

A further object of the invention is to accomplish the above mentioned object in a simple and reliable manner without the use of additional relays or other operating 30 parts and without the use of complicated apparatus.

Other objects and advantages will appear as the description of the invention progresses, and the novel features of the invention will be particularly pointed out in the appended claims.

In describing the invention in detail reference is had to the accompanying drawing in which is illustrated a preferred physical 40 embodiment of the invention, in which like reference characters designate like parts in the several views, and in which:

Figure 1 is a diagrammatic view showing a portion of a railroad track and signals for 45 governing traffic over said portion of track, together with the controlling devices for governing these signals and the electrical connections constituting the operating and controlling circuits; and,

50 Fig. 2 is a fragmentary view showing one way in which one contact finger of a relay may be made to lag behind the operation of the other contact fingers of that same relay, this or a similar modification of the ordinary 55 construction of a track relay being used in

the absolute permissive block signaling system embodying this invention.

Since a system for governing the movements of trains over a stretch of single track having passing sidings at intervals is shown 60 in detail and fully described in my prior application above mentioned, there is illustrated in the accompanying drawing for simplicity, only a part of the complete system, which is, however, sufficient to enable a 65 clear understanding of the construction and operation of the improvement embodying this invention; and since the control of the various signals used in a complete absolute permissive block signal system is clearly 70 shown and described at length in my prior application above mentioned, the controlling circuits shown in the accompanying drawing have been simplified by omitting the construction and arrangement of parts and 75 the controlling circuits which give the forty-five degree or caution position of the signals.

In the accompanying drawing, numerals 1 and 2 designate a portion or stretch of single track which is divided into track sections of suitable length by insulating joints 3, there being shown two complete track sections, designated B and C and the adjacent ends of two other track sections designated A and D. Traffic over the stretch of 80 track illustrated may be in either direction, either from left to right, as indicated by the arrow X, or from right to left as indicated by the arrow Y. Located at the left hand end of the track section B is a signal 4 for governing traffic in the direction indicated by the arrow X, and at the left hand end of the track section D is another signal 5 for governing traffic in the same direction. Located at the right hand end of the track 90 section C is a signal 7 for governing traffic in the direction indicated by the arrow Y, and located at the right hand end of the track section A is another signal 6 for governing traffic in the same direction. Since 95 the improvement embodying this invention has to deal more with the controlling circuits for the signals 4 and 7 governing traffic in opposite directions over the track sections B and C, and commonly termed opposing signals, only the controlling devices and circuits associated with these signals 4 and 7 are illustrated; but it should be understood that the controlling devices and 100 circuits for the signal 5 are the same as those 105 for the signal 7. The signals 4 and 7 are 110

for the signal 4 and in the same way the controlling circuits and devices associated with the signal 6 are the same as those associated with the signal 7. The signals 4, 5, 6 and 7 may be any one of the well known and approved types used at the present day either in single track signaling systems or double track signaling systems, and in the particular embodiment of the invention illustrated, the signals are of the well known semaphore type and in general consist of an operating motor for moving the semaphore arm from a horizontal or biased position, which may be termed a stop or danger position, to an operated position or positions, which may indicate clear or caution, together with suitable means for retaining the semaphore arm in its operated position or positions. In the particular embodiment of the invention illustrated, the semaphores have only two positions, namely, a horizontal or stop position, and a vertical or clear position; but it should be understood that according to approved signaling practice these semaphores are constructed and controlled so as to have three positions for indicating full clear, caution, and danger or stop, and such an arrangement is shown in my prior application above mentioned. However, this invention is fundamentally in no way dependent upon the use of three position semaphore signals and may be advantageously applied without material change or modification to signal systems in which two two-position signals arranged as home and distant signals are employed, or to signaling systems in which signals of any suitable type are used. This invention has been shown in connection with the controlling circuits and devices for signals commonly termed intermediate signals, which control traffic along a stretch or portion of single track between two passing sidings; and as explained at length in my prior application above mentioned, these signals 4 to 7, inclusive, are of the type commonly known as permissive signals; but since the characteristics of this type of signal are well known in the art, it is deemed unnecessary to further discuss the significance of these signals or describe in detail how the signals are constructed so as to enable the engineer to differentiate between them as permissive signals and other signals along the railroad. The improvement embodying this invention is more especially concerned with signaling systems in which some or all of the signals and their controlling devices are supplied with current from a single source; and as an illustration of this type of signaling system there is shown in the accompanying drawing a suitable alternating current generator 8 connected to line wires 9 and 10, which are carried on poles or in any other suitable way along the portion of the rail-

road track which is signaled. Opposite the adjacent ends of the track sections B and C is located a track transformer 11, the primary of which is connected in the usual way across the line wires 9 and 10. The secondary of the transformer 11 is provided with two windings 12 and 13, which are connected in the usual way across the track rails 1 and 2 at the ends of the track sections B and C, respectively. At the right hand end of the track section A a track relay 14, of suitable construction and capable of being operated by alternating current, is connected in the usual way across the track rails 1 and 2 of said track section; and in a like manner track relays 15, 16 and 17 are connected to the track sections B, C and D. These track relays are provided with armatures or contact fingers which are illustrated conventionally and are given, for convenience, the same reference characters as the corresponding relay with a distinctive exponent added thereto. While these track relays may be, as stated, of any suitable construction, one contact finger of each relay is so arranged or constructed as to lag behind the operation of the other contact fingers of the relay, when that relay is energized or picked up. This lagging operation of one contact finger of each track relay may be obtained in different ways, and may result from a special construction of the relay itself or from a special attachment or controlling means for one of the contact fingers of the relay. One simple arrangement and construction capable of performing the functions necessary for use in the system embodying this invention is shown in Fig. 2, and is more fully described hereinafter.

Associated with each of the signals 4, 5, 6 and 7 is a relay hereinafter termed a line relay, the relays for the signals 4 and 7 only being shown and being designated 18 and 19. Also associated with each of the signals 4 to 7, inclusive, is a relay hereinafter termed a stick relay, the stick relays associated with the signals 4 and 7 only being shown, and being designated 20 and 21. The armatures or contact fingers of the line relays 18 and 19 and the stick relays 20 and 21 are shown according to established convention and are given the same reference characters as the corresponding relay with distinctive exponents added thereto. Associated with the signals 4 and 6 is a transformer T^1 , having its primary connected across the line wires 9 and 10 and having a secondary 22 connected by conductors to the various conductors and circuits used for controlling the relays and the semaphore operating mechanism for said signals 4 and 6, and in a similar way the transformer T^2 having the secondary 23 is associated with the signals 5 and 7. Associated with each of the signals 4 to 7, inclusive, is a circuit controller which is

represented according to established convention, and which is operatively connected to the corresponding semaphore or semaphore operating mechanism, only the circuit controllers associated with the signals 4 and 7 being shown and being designated 24 and 25. These circuit controllers 24 and 25 are closed when the corresponding semaphores occupy the vertical position or the diagonal position, or any position between the vertical position and the diagonal position, the exact extent of the angular movement of the semaphore during which the circuit controller is closed being dependent upon the operating characteristics of the semaphore and its controlling relays, as will be made more clear hereinafter.

Although certain relays are herein designated track relays, certain others as line relays, and certain others as stick relays, these designations are chosen for the sake of convenience in description; and it should be understood that there is ordinarily in practice no essential difference in the construction of the relays so designated, with the possible exception of the track relays, each of which, as explained hereinbefore, has one contact finger which lags in its movement behind the movement of the other contact fingers when that track relay is picked up. Each of the relays above mentioned are preferably designed to be operated by alternating current in a way which will be clearly understood by those skilled in the art of railway signaling.

Extending the length of the railroad track protected by the signaling system is a common wire designated 26, and which, as will be readily understood by those skilled in the art of railway signaling, constitutes a common conductor for circuits connecting the different signal locations.

The operation of the signaling system disclosed in my prior application above mentioned is set forth at length in said application, and in order to obtain a clear understanding of the improvement embodying this invention, it will be necessary to refer to the operation of this system as a whole only briefly. Generally stated the operation of the system disclosed in my prior application is such that when a train is traveling over the stretch of single track between passing sidings in one direction, as for instance, in the direction indicated by the arrow X, the opposing signals governing traffic in the opposite direction, as the signals 6 and 7, are all caused to assume their biased or stop position, thereby blocking the opposing movement of trains, while signals governing traffic in the direction in which the train is traveling, as the signals 4 and 5, are allowed to move successively first to their forty-five degree or caution position, and then to their ninety degree or full proceed

position as the train advances. As fully shown and described in my prior application this control of the signals is obtained by the use of line relays each of which is controlled by the line relay associated with the next signal in advance governing traffic in the same direction as well as by the track relays of the track sections protected by the corresponding signal; and by arranging a stick relay such that this stick relay at a signal will be energized when a train passes that signal and is moving in the direction of traffic governed thereby, and such that this stick relay when energized will prevent the line relay of the corresponding signal from controlling the line relay of the next signal in the rear. The controlling circuits of the line relays are not shown in their entirety in the accompanying drawing, since this drawing, as explained hereinbefore, shows only part of the signaling system, but since the control of the line relay 18 associated with the signal 4 is the same as that of the line relay (not shown) associated with the signal (not shown) located at the left of the signal 4, the complete circuit for controlling the line relay 18 may be readily determined as follows:

Commencing at the common wire 26, conductors 27, 28 and 29, line relay 18, conductor 30, armature 15³ of the track relay 15 in its upper position, conductor 31, armature 16³ of the track relay 16 in its upper position, conductor 32, armature 21³ of the stick relay 21 in its lower position, conductor 33 and thence to the line relay (not shown) associated with the signal 5.

This line relay associated with the signal 5 controls the circuit for the line relay 18 in the same way as the line relay 18 controls the line relay of the signal (not shown) to the left of the signal 4, that part of the circuit for this latter line relay shown in Fig. 1 being along conductor 34, armature 14¹ of the track relay 14 in its upper position, conductors 35 and 36, armature 18¹ of the line relay 18 in its upper position, conductors 37, 38 and 39, secondary 22 of the transformer T¹, conductors 40, 41, 28 and 27 to the common wire 26.

In other words, the conductor 33 of the circuit for controlling the line relay 18 corresponds to the conductor 35 for controlling the line relay of the signal to the left of the signal 4, and from the circuit for controlling this latter relay, it can be seen that the controlling circuit for the line relay 18 after passing through the armature 16³ of the track relay 16 and the armature 21³ of the stick relay 21 may be traced along conductor 33, through a front point of an armature of the line relay (not shown) associated with the signal 5, thence through the secondary of the transformer T², and back to the common wire 26. From this

it can be seen that when the line relay associated with the signal 5 is deenergized, either because of a train occupying the track section protected by the signal 5 or 5 because of the deenergization of the line relay associated with the signal, if there be one, at the right of the signal 5, said line relay at the signal 5 will cause the deenergization of the line relay 18 at the 10 signal 4, which line relay 18 in turn causes a deenergization of the line relay associated with the signal, if there be one, at the left of the signal 4.

The armature of each line relay, as the 15 armature 18¹ of the line relay 18, which controls the circuit of the line relay for the signal in the rear is shunted when the corresponding stick relay, as the stick relay 20, is energized, this shunt in connection 20 with the armature 18¹ being as follows: Commencing at the conductor 36, along conductor 42, armature 20² of the stick relay 20 in its upper position, and conductors 43 and 37. In this way when the stick relay 25 20 is energized, current may be supplied from the secondary 22 of the transformer T¹ to conductor 34, leading to the line relay (not shown) at the left of the signal 4, although the line relay 18 at the 30 time is deenergized.

The controlling circuit for the line relay 19 associated with the signal 7 is the same as the controlling circuit hereinbefore discussed for the line relay 18, that part 35 of the controlling circuit for the line relay 19 which is shown in Fig. 1 being as follows: commencing at the common wire 26, conductors 88, 89 and 44, relay 19, conductor 45, armature 16² of the track relay 16 in its upper position, conductor 46, armature 15² of the track relay 15 in its upper position, conductor 47, armature 20³ of the stick relay 20 in its lower position, conductor 48, and thence through a front point on 40 an armature of the line relay associated with the signal 6.

The line relay 19 acts conjointly with the stick relay 21 to govern the controlling circuit of the line relay associated with 50 the signal (not shown) at the right of the signal 7 and governing traffic in the same direction; but since this shunt and controlling circuit is the same as that already described in connection with the line relay 18, no further description is necessary.

When each line relay is energized the operating mechanism of the corresponding signal is supplied with current which operates the semaphore arm of the signal to 55 its vertical position, as shown in the drawing, and holds it in that position. The operating circuit for the signal 4 may be traced as follows: commencing at the right hand terminal of the secondary 22 of the transformer T¹, conductors 39, 38, 37 and 60

49, armature 18² of the line relay 18 in its upper position, conductor 50, operating mechanism of the signal 4 (not shown), and conductors 51, 52 and 40, back to the other terminal of the secondary 22. 70

In a similar way the operating circuit for the signal 7 may be traced as follows: commencing at the right hand terminal of the secondary 23 of the transformer T², conductors 53, 54, 55 and 56, armature 19² of the line relay 19 in its upper position, conductor 57, operating mechanism of the signal 7, and conductors 58, 59 and 60, back to the other terminal of said secondary 23. 75

As stated hereinbefore, the stick relay associated with a signal is energized when a train is moving in the direction of traffic governed by that signal and passes said signal. The preliminary energizing or pick up circuit for the stick relay 20 may be traced 80 as follows: commencing at the right hand terminal of the secondary 22 of the transformer T¹, conductors 39 and 61, circuit controller 24 of the signal 4 closed, conductor 62, armature 15¹ of the track relay 15 in 85 its lower position, conductors 63 and 64, stick relay 20, conductor 65, and thence either along conductor 66, armature 15⁴ of the track relay 15 in either its lower or upper position, and conductors 67 or 68, 69, 52 and 90 40 to the other terminal of said secondary 22, or from said conductor 65 along conductor 70, armature 14² of the track relay 14 in either its upper or lower position, conductor 71 or 72, and conductors 73, 28, 41 and 40 95 to the other terminal of said secondary 22. 100

The maintaining or stick circuit for the stick relay 20 may be traced as follows: commencing at the right hand terminal of the secondary 22 of the transformer T¹, conductors 39, 38, 37 and 49, armature 18² of the line relay 18 in its lower position, conductor 74, armature 20¹ in its upper position, conductors 75 and 64, stick relay 20, conductor 65, and thence through either the armature 14² of the track relay 14 or the armature 15⁴ 105 of the track relay 15, when either of said armatures are in either their upper or lower position, and back to the other terminal of the secondary 22 in the same way as above 110 described in connection with the pick up circuit for the stick relay 20. 115

The pick up circuits for the stick relay 21 is the same in effect as that of the stick relay 20, and may be traced as follows: commencing at the right hand terminal of the secondary 23 of the transformer T², conductor 53, circuit controller 25 of the signal 7 closed, conductor 76, armature 16¹ of the track relay 16 in its lower position, conductors 77 and 78, stick relay 21, conductor 79, and thence either along conductor 80, armature 17² of the track relay 17 in either its upper or lower position, conductor 81 or 82 and conductors 83, 89, 90, 59 and 60, back to the other ter- 125 130

5
minal of the secondary 23, or from said conductor 79 along conductor 84, conductor 85 or 86, armature 16⁴ of the track relay 16 in either its upper or lower position, and conductors 87 and 60 to the other terminal of said secondary 23.

10
The stick circuit for the stick relay 21 may be traced as follows: commencing at the right hand terminal of the secondary 23 of the transformer T², conductors 53, 54, 55 and 56, armature 19² of the line relay 19 in its lower position, conductor 91, armature 21¹ of the stick relay 21 in its upper position, conductors 92 and 78, stick relay 21, conductor 79, and thence along conductor 80 or conductor 84 through either the armature 16⁴ or the armature 17² in either the upper or lower position, to the other terminal of the secondary 23 in the same way as above described for the pick up circuit of the stick relay 21.

15
The armatures 14², 15⁴, 16⁴ and 17² included in the pick up and stick up circuits for the stick relays 20 and 21 are indicated 20 in Fig. 1 as provided with a suitable device, designated generally R, which device is designed to retard the upward movement of these armatures when the corresponding track relays have been deenergized and are 25 reenergized. The upward movement of these armatures may be retarded in various ways; but one simple means, consisting of a dash-pot attachment, is shown in Fig. 2 as applied to a relay of well known construction. The construction of the contact fingers in this relay, the manner of supporting and operating them, is like that shown in the 30 patents to W. K. Howe, 1,012,081 of December 19, 1911, and 1,019,047 of March 5th, 1912; and since the construction is fully described in these patents it will be necessary 35 to refer only briefly to the construction of the parts as they are shown in Fig. 2. Referring to Fig. 2, there is illustrated the 40 usual contact carrying block 93 of suitable insulating material, which is supported by suitable brackets or arms, so as to be capable of oscillating on a horizontal axis, only one of these brackets designated 94, is shown in 45 Fig. 2; and fixed to the contact block 93 is an arm 95 to which is connected a link 96 which serves to connect the arm 95 with a motor or other means used for operating the 50 relay. The contact carrier block 93 supports 55 two contact fingers 97 and 98, one of which, 97, presses against the fixed contact pieces 99 when said contact finger 97 is in its upper position, while the other contact finger 98, when in its upper position, presses 60 against a contact piece 100, and when in its lower position, presses against a contact piece 101. To the contact finger 98 is rigidly 65 fixed a rod 102, the lower end of which is bent up and has fastened thereto a piston 103 including a flexible disk of leather or

similar material; and the piston 103 is arranged to move up and down in a dash-pot cylinder 104 fastened to some fixed part of the relay, said dash-pot cylinder 104 having a small hole 105 therein in its upper end. 70 The operation of the dash-pot attachment for the contact finger 98 will be readily apparent, it being obvious that the piston 103 may move downwardly in the dash-pot cylinder 104 with little opposition, but can 75 move upwardly from its lower position, shown in Fig. 2, only as fast as the air in said cylinder can escape through the small hole 105. In this way when the relay is deenergized and the arm 95 is raised to the 80 position shown in Fig. 2, the contact finger 98 will be moved downwardly simultaneously with the contact finger 97, whereas, when the arm 95 is pulled to its lower position, thereby raising the contact finger 97, 85 the contact finger 98 is retarded by the dash-pot attachment and will assume its upper position, in which it presses against the contact piece 100, only after the lapse of a short 90 interval of time dependent upon the adjustment of the dash-pot device.

95
As stated hereinbefore, the purpose of this invention is to prevent interference with the proper operation of the system by a temporary interruption of the current supplied from a single source; but before considering the operation of the system under the particular conditions existing when the current supplied to the system is temporarily interrupted, it seems expedient to describe briefly 100 the operation of the part of the system shown in the accompanying drawing under normal operating conditions, it being considered sufficient in view of the full illustration and description of the system in my prior application above mentioned, to describe in a general way the operation for a train moving in one direction only. Assuming the signals 4 to 7 inclusive and their controlling devices are in the position as shown 105 in Fig. 1, suppose a train moving from left to right, in the direction indicated by the arrow X, enters into the stretch of single track in which the track sections A, B, C and D form a part. This train movement causes all of the signals, including the signals 6 and 7, governing traffic in the opposite direction, to assume their stop positions by reason of the successive deenergization of 110 the line relays associated with these signals, and also causes the signal, governing traffic in the same direction in which the train is moving and protecting the track section now occupied by the train, to assume its stop position. Consider that this train advances 115 until it occupies the track section A, then the dropping of the armature 14¹ of the track relay 14 interrupts the circuit leading from the conductor 34 to the line relay (not shown) to the left of the signal 4 and gov- 120

125
130

erning traffic in the same direction. As the train advances and enters the track section B, the pick up circuit for the stick relay 20 is energized, since the signal 4 is in its vertical position and the circuit controller 24 is closed, and since the armature 15¹ of the track relay 15 drops. The dropping of the armature 15² interrupts the controlling circuit for the line relay 18, thereby causing its armature 18² to assume its lower position, whereby the stick circuit for the stick relay 20 is established. In this connection it should be noted that the armatures 14² and 15⁴ of the track relays 14 and 15, respectively, which are provided with the dash-pot attachment R are successively moved to their lower positions, so that one or the other of these armatures maintains the path from the stick relay 20 to the left hand terminal of the secondary 22 of the transformer T¹. In other words, while the train is in the track section A, the armature 14² of the track relay 14, being in its lower position, maintains the above mentioned path; and when the train enters the block B the armature 15⁴ drops unimpeded by the dash-pot attachment and establishes another path for current to flow from the stick relay 20 to the secondary 22, so that when the train leaves the track section A and the armature 14² gradually assumes its upper position, the armature 15⁴ being held in its lower position by the train on the track section B, maintains said conducting path, and by the time the train leaves the track section B, the armature 14² has assumed its upper position and maintains said conducting path while the armature 15⁴ is gradually moving from its lower position to its upper position. In this way the dash-pot attachment R to the armatures 14² and 15⁴ does not interfere in any way with the proper making of the pick up and stick up circuits of the stick relay 20 during the normal operation of the system.

When the stick relay 20 is energized, its armature 20² establishes the shunt hereinbefore traced for the armature 18¹ of the line relay 18, so that, although the track section B is now occupied by the train and the line relay 18 is deenergized, the line relay associated with the signal at the left of the signal 4 and governing traffic in the same direction may be energized as soon as the train has entirely left the track section A, thereby permitting said signal to the left to assume an-operated position to permit another train to follow the first train. In a similar way the movement of the first train past the signal 5 permits the signal 4 to assume an operated position, due to the picking up and the sticking up of the stick relay associated with the signal 5, and the same operation occurs at the successive signals governing traffic from left to right until the first train has

left the stretch of single track. A similar operation occurs for a train traveling in the direction indicated by the arrow Y; and in this case the signals 5 and 4 are moved to their stop position, while, due to the energization of the stick relays associated with the signals 6 and 7, these signals and other signals at the right of the signal 7 and governing traffic in the same direction are allowed to assume the operated position successively.

It should be noted that when the stick relay 20 is energized the armature 20³ of this relay interrupts the controlling circuit hereinbefore traced for the line relay 19, so that, while the stick relay 20 is energized, the line relay 19 must be deenergized. One purpose of this control is to check the operation of the stick relay 20, so that, if the armatures of this stick relay for any reason fail to return to their lower position when this relay is deenergized, the opposing signal, namely the signal 7, will be held in its stop position. In a similar way the controlling circuit for the line relay 18 associated with the signal 4 is controlled by the armature 21³ of the stick relay 21 associated with the signal 7, which signal 7 governs traffic in the opposite direction.

To enable a clear understanding of the nature of the improvement embodying this invention, it will be necessary to explain the difficulty encountered in systems wherein the current for operating the signals and their controlling devices for a portion of a railroad is derived from a single source, in case this supply of current is temporarily interrupted; and for this purpose assume that armatures 14², 15⁴, 16⁴ and 17², together with their retarding device R, are omitted, and that the conductor 65 of the stick relay 20 is directly connected to the left hand terminal of the secondary 22 of the transformer T¹, and that the conductor 79 of the stick relay 21 is similarly directly connected to the left hand terminal of the secondary 23 of the transformer T², this direct connection being the same as that used in the signaling system disclosed in my prior application above mentioned. Suppose now that the supply of current to the different relays of the signaling system is temporarily interrupted, this being not an infrequent occurrence where an alternating current transmission line is used, since the requirements of operation, such as switching at the central station, sometimes result in the power being taken from the transmission line for a very short time. When the current supplied to the different relays is first cut off the armatures of all these relays drop and the semaphore arms of the different signals gradually move toward their biased or horizontal position, if they are not already there. Suppose that the interruption to the

current is very brief and that the semaphore arm of a signal, as for instance the signal 4, is not moved far enough toward its horizontal position to open the circuit controller, as the circuit controller 24, governed by that signal, before the current is reapplied. Under these conditions the pick up circuit for the different stick relays is closed, for the reason that, referring to the stick relay 20, the armature 15¹ is in its lower position and the circuit controller 24 is still closed. Although the reapplying of the current reenergizes the track relay 15 and immediately causes the armature 15¹ of this relay to move from its lower position, the armatures of the stick relay 20 are simultaneously moved, and it is possible, and in fact in practice a likely occurrence, for the armatures of the stick relay 20 to be raised to their upper position. When the armature 20³ of the stick relay 20 is raised, it opens a break in the controlling circuit for the line relay 19, so that this line relay will remain deenergized; and in a similar way the armature 21³ of the stick relay 21, when raised, interrupts the controlling circuit for the line relay 18 and maintains that line relay deenergized. As pointed out, the stick relay 20 and 21, if the interruption of the supply of current is only brief, will be both energized, and it can be readily seen that the energization of both of these stick relays results in a deenergization of both of the line relays 18 and 19; and since the armature 18² of the line relay 18 is in its lower position, the stick circuit for the stick relay 20 is established, and similarly since the armature 19² of the line relay 19 is in its lower position, the stick circuit for the stick relay 21 is established. In short, if the cessation of current is of the right duration it is possible for both of the stick relays 20 and 21 to be stuck up and this results in the two opposing signals 4 and 7 being both placed in the horizontal or stop position and remaining there, thereby seriously interfering with the movement of traffic.

The difficulty above described is, however, obviated by the use of the armatures 14², 15⁴, 16⁴ and 17² and some device such as illustrated in Fig. 2 for retarding the upward or pickup movement of these armatures. It has already been seen that these armatures and the retarding attachment do not affect the normal operation of the system; but in case there is a temporary interruption in the supply of current, the action of these armatures is such as to obviate the difficulty above described. To illustrate, assume similar conditions to those above assumed, that is, that the current is temporarily cut off, but is reapplied before the semaphore arms of the signal which are

in the vertical position move far enough toward their horizontal position to open the circuit controllers governed thereby. Referring to the stick relay 20, when the current is first reapplied the armatures 15¹, 14² 70 and 15⁴ are in their lower position, and, consequently, the pick up circuit for the stick relay 20 is temporarily established as before; but shortly after the current is reapplied to the track relays 14 and 15, the armatures 14² and 15⁴ of these track relays, respectively, move upward far enough to break contact with the conductors 72 and 68, respectively, thereby interrupting both the pick up circuit and the stick up circuit for 80 the stick relay 20. The dash-pot attachments for the armatures 14² and 15⁴ are preferably so adjusted that before these armatures rise far enough to make contact with conductors 71 and 67, respectively, sufficient time will have elapsed for the armatures of the stick relay 20 to drop. In this way the pick up circuit for the stick relay 20, which is initially established, is broken at armature 15¹, and the stick circuit for said stick 90 relay 20 is broken at the armature 20¹, with the result that the stick relay 20 will not be improperly picked up by the temporary cessation of the current.

Although I have particularly described 95 the construction of one physical embodiment of my invention, and explained the operation and principle thereof; nevertheless, I desire to have it understood that the form selected is merely illustrative, but does not 100 exhaust the possible physical embodiments of the idea of means underlying my invention.

What I claim as new and desire to secure by Letters Patent of the United States, is:— 105

1. In a signaling system for railroads, in combination: a stretch of track divided into track circuit sections; a first signal and a second signal for governing traffic in opposite directions over said stretch; a controlling circuit for each signal; a stick relay associated with each signal; means controlled by each stick relay for interrupting the controlling circuit for the opposing signal when that stick relay is energized; a 110 pick up circuit for each relay; a stick circuit for each stick relay; and means governed by the track circuits of two track sections adjacent to each signal for temporarily interrupting both the pick up circuit and 115 the stick up circuit for the corresponding stick relay when said track circuits are simultaneously reenergized.
2. In a signaling system for railroads, in combination: a stretch of track divided into 120 track circuit sections; a signal for governing traffic over said stretch; a circuit controller governed by said signal and closed when a portion of said stretch of track governed by 125 that signal is not occupied, said circuit con-

- troller temporarily remaining in its closed position after said portion of track is occupied; a stick relay; a pick up circuit for said relay including said circuit controller and governed by a track circuit section adjacent to said signal; a stick circuit for said stick relay controlled by the relay itself and by the track circuit sections of the portion of track protected by said signal; means 5 governed by the track circuits of two track sections adjacent to said signal for temporarily interrupting both said pick up circuit and said stick up circuit when said track sections are simultaneously reenergized; and 10 means for signaling controlled by said stick relay.

3. In a signaling system for railroads, in combination: a stretch of track divided into track circuit sections; a stick relay governed 20 by the track circuits of a portion of said stretch of track; means for preliminarily energizing said stick relay by the movement of a train in one direction over said portion of track; means for maintaining said relay energized after it has been initially energized and so long as said portion of track is occupied; and means governed by two track circuits of said portion of track for rendering said last mentioned means temporarily ineffective when these two track 25 circuits are simultaneously reenergized.

4. In a signaling system for railroads, in combination: a stretch of single track divided into track circuit sections; signals for 30 governing traffic in opposite directions over a portion of said stretch; a controlling circuit for each signal which is governed by the track circuits of the track sections protected thereby; a normally deenergized 35 stick relay associated with each signal; means controlled by each stick relay for interrupting the controlling circuit for the other signal when that stick relay is energized; a stick circuit for each relay governed 40 by the controlling circuit of the corresponding signal; a pickup circuit for each relay controlled by some of said track circuit sections; a common source of current for said 45 circuits including the track circuits; and means for temporarily preventing energization 50 of said relays upon resumption of the supply of current from said source after an interruption.

5. In a signaling system for railroads, divided into track sections provided with 55 normally closed track circuits supplied with current from a common source, the combination with a normally deenergized stick relay, of a governing circuit for said relay controlled by some of said track circuits, and means normally inactive when current is 60 continuously supplied from said source for causing a temporary interruption in said circuit when the supply of current from the

said source is established after an interruption. 65

6. In a signaling system for railroads, divided into track sections provided with normally closed track circuits and having a common source of current for its circuits 70 including the track circuits, the combination with a normally deenergized stick relay, of an energizing circuit for said relay, means including a slow-acting normally closed circuit controller for governing said 75 energizing circuit, and means for temporarily preventing energization of said relay when the supply of current from said source is established after an interruption. 80

7. In a signaling system for railroads, divided into track sections provided with normally closed track circuits and having a common source of current for its circuits including the track circuits, the combination with a stick relay, of controlling circuits 85 for initiating and maintaining a change in the condition of said relay, and means controlled by two adjacent track circuits for temporarily rendering said controlling circuits ineffective when the track relays of 90 said track circuits are simultaneously reenergized.

8. In a signaling system for railroads, divided into track sections provided with normally closed track circuits and having a 95 common source of current for its circuits including the track circuits, the combination with a stick relay, of a controlling circuit for said relay including two branches in multiple, a slow-acting circuit controller included in each branch, said circuit controllers being governed separately by the track relays of two adjacent track circuits and being closed when the corresponding 100 track relay is either energized or deenergized, whereby the continuity of the controlling circuit for said relay is maintained at one or the other of said circuit controllers during the normal operation of the track relays in a sequence by a train moving over the track, but is interrupted when said track relays are simultaneously reenergized. 105

9. In a signaling system for railroads, the combination with two adjacent track circuit sections each having a track relay 110 and a common source of current, of a circuit for signaling including two branches in multiple, circuit controllers governed separately by said track relays and included one in each of said branches, said circuit controllers being closed when the corresponding track relay is energized or deenergized and being slow-acting in changing from one closed position to the other when its track relay is energized, whereby said circuit for signaling is temporarily interrupted when said track relays are simultaneously reenergized by the resumption of the flow of cur- 115 120 125

rent from said source after an interruption.

10. In a signaling system for railroads having normally closed track circuits and a common source of current for its circuits including the track circuits, the combination with two electrically operable devices at different points along the track controlled by certain track circuits, controlling circuits for each device for causing that device to be automatically changed from its normal condition by a predetermined operation of the track relays of its controlling track circuits, said devices being normally operated by train movements in opposite directions at different times and having their controlling circuits inter-connected to prevent the operation of either device when the other is in its changed condition, and means associated with each device for preventing a change in the condition thereof when its controlling track circuits are simultaneously re-energized by a resumption of the flow of current from said source after an interruption.
- 25 11. In a signaling system for railroads, having a track divided into track circuit sections each provided with a normally closed track circuit, the combination with signals for governing traffic in opposite directions, a controlling circuit for each signal governed by the track circuits of the track sections protected thereby, a normally de-energized stick relay associated with each signal, means controlled by each stick relay for interrupting the controlling circuit for the other signal when that stick relay is energized, a stick circuit for each stick relay governed by the controlling circuit of the corresponding signal, an energizing circuit for each stick relay including a slow-acting

normally closed circuit controller governed by the controlling circuit of the corresponding signal, a common source of current for said circuits including the track circuits, and means controlled by two adjacent track circuits for temporarily interrupting the energizing circuit of each stick relay when current is simultaneously supplied to said track circuits after an interruption.

- 10 12. In a signaling system for railroads, having a track divided into track circuit sections each provided with a normally closed track circuit, the combination with signals for governing traffic in opposite directions, a controlling circuit for each signal governed by the track circuits of the track sections protected thereby, a normally de-energized stick relay associated with each signal, means controlled by each stick relay for interrupting the controlling circuit for the other signal when that stick relay is energized, a stick circuit for each stick relay governed by the controlling circuit of the corresponding signal, an energizing circuit for each stick relay including a slow-acting 55 normally closed circuit controller governed by the controlling circuit of the corresponding signal, a common source of current for said circuits including the track circuits, the stick circuit and energizing circuit of each 60 stick relay including two common branches in multiple, and a slow-acting circuit controlling means included in each branch, said circuit controlling means being governed separately by two adjacent track circuits 65 and being closed when the corresponding track relay is either energized or de-energized.

SEDGWICK N. WIGHT.
